The ornamental design for an endoscopy training module, as shown and described.

DESCRIPTION

FIG. 1 is a perspective view of an endoscopy training module showing our new design;

FIG. 2 is a front elevation view of the endoscopy training module illustrated in FIG. 1;

FIG. 3 is a back elevation view of the endoscopy training module illustrated in FIG. 1;

FIG. 4 is a left side elevation view of the endoscopy training module illustrated in FIG. 1;

FIG. 5 is a right side elevation view of the endoscopy training module illustrated in FIG. 1;

FIG. 6 is a top plan view of the endoscopy training module illustrated in FIG. 1; and,

FIG. 7 is a bottom plan view of the endoscopy training module illustrated in FIG. 1.

The broken lines are directed to environment and are for illustrative purposes only. The broken lines form no part of the claimed design.
